Primary Examiner — Mary Ann Calabrese*Assistant Examiner* — Messina L Smith(74) *Attorney, Agent, or Firm* — Bergman & Song LLP;
Michael Bergman(57) **CLAIM**

The ornamental design for a pour top for beverage container, as shown and described.

DESCRIPTION

FIG. 1 is a perspective view of a pour top for beverage container according to the design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines shown in the drawings illustrate portions of the pour top for beverage container that form no part of the claimed design.
